US00D965034S

(12) **United States Design Patent** (10) **Patent No.:** **US D965,034 S**
Deng et al. (45) **Date of Patent:** **** Sep. 27, 2022**

(54) **PORTABLE REFRIGERATOR**

(71) Applicant: **GUANGZHOU DAOHE TECHNOLOGY CO., LTD.**,
 Guangzhou (CN)

(72) Inventors: **Tingliang Deng**, Guangzhou (CN);
Guangyang Li, Guangzhou (CN)

(73) Assignee: **GUANGZHOU DAOHE TECHNOLOGY CO., LTD.**,
 Guangzhou (CN)

(**) Term: **15 Years**

(21) Appl. No.: **29/841,333**

(22) Filed: **Jun. 6, 2022**

(51) LOC (13) Cl. **15-07**

(57) **CLAIM**

The ornamental design for a portable refrigerator, as shown and described.

DESCRIPTION

FIG. 1 is a perspective view of a portable refrigerator showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the portable refrigerator where the portable refrigerator is in a configuration of use;

FIG. 10 is an enlarged view of portion 10 shown in FIG. 1; and,

FIG. 11 is an enlarged view of portion 11 shown in FIG. 1. The dash-dash broken lines in the drawings depict portions of the portable refrigerator that form no part of the claimed design. The dot-dash broken lines represent boundaries of the enlarged portions and form no part of the claimed design.

1 Claim, 11 Drawing Sheets
